UNITED STATES PATENT OFFICE.

HUBERT K. HENRY, OF DETROIT, MICHIGAN, ASSIGNOR, BY MESNE ASSIGNMENTS, TO REX TYPEWRITER COMPANY INCORPORATED, OF FOND DU LAC, WISCONSIN, A CORPORATION OF VIRGINIA.

TYPEWRITING-MACHINE.

1,387,543.

Specification of Letters Patent. Patented Aug. 16, 1921.

Application filed January 18, 1918. Serial No. 212,444.

To all whom it may concern:

Be it known that I, HUBERT K. HENRY, a citizen of the United States, and a resident of Detroit, county of Wayne, and State of Michigan, have invented certain new and useful Improvements in Typewriting-Machines, of which the following is a full, clear, and exact description.

The invention relates to typewriting machines and more particularly to the case shift mechanism for bringing any one of a number of different sets of type into operation. The invention seeks to provide a simple and effective case shift mechanism more particularly adapted for effecting the vertical shift of a frame which supports the paper carriage in a front strike typewriter having type bars, each provided with two and preferably with three type. The invention consists in the features of improvement hereinafter set forth, illustrated in the preferred form in the accompanying drawings and more particularly pointed out in the appended claims.

In the drawings Figure 1 is a longitudinal section of a typewriting machine to which the present improved shift mechanism is applied, with the parts shown in normal position. Figs. 1^a and 1^b are detail sections on lines *a* and *b* of Fig. 1. Fig. 2 is a longitudinal section with the parts shown in shifted position. Fig. 3 is a partial view showing another position of the shift mechanism. Fig. 3^a is a detail section on line *a* of Fig. 3. Fig. 4 is a rear view of the shift mechanism, the side plates of the machine being shown in section.

The machine frame comprises side plates 10 preferably formed of sheet metal, and connected at the lower front and rear corners by transverse bars 11 and 12, and at their upper rear corners by a transverse rod 13. A vertically disposed, type bar support or segment 14, which is preferably quite heavy and formed of cast metal, extends between the side plates somewhat in advance of the rear edges thereof and with the upper portion of the segment adjacent the upper

edges of the side plates, the segment being securely fastened to the side plates by screws 15. The type bar support is provided on its rear face with a strengthening flange or flanges 16 and on its front face with a forwardly projecting segmental rib 17. This rib is provided with a series of radial slots 55 which receive the rear ends of the type bars 18 and, on its under side, the rib is provided with a seat for the type bar pivot rod 19.

In normal position, the type bars extend 60 forwardly from the type bar segment and their forward ends are supported upon a segmental rest 20 which in turn, is carried by a transverse bar or plate 21 that extends between and is secured to the side plates 65 10. Horizontal key levers 22 are pivoted between their ends upon a series of transverse pivotal rods 23 and are provided with keys 24 at their forward ends. The downturned edges of the transverse bar or plate 21 form 70 guiding comb bars 25 for the key levers and the rear ends of the latter are connected by links 26 to the type bars at points adjacent and in front of the type bar pivot rod 19. Each type bar is provided with a head 27 75 carrying three type and the type bars or key levers are provided with suitable return springs (not shown) for holding the bars in normal position. For the sake of clearness, only a single type bar and key lever 80 are shown, but it will be understood that the type bars are operated by the key levers to project the type thereon upwardly and rearwardly to a common printing point at the front of a paper supporting platen. The 85 paper supporting platen or cylinder 28 is journaled between the end plates 29 of a paper carriage, the plates 29 in the form shown being integral with and upturned from a transverse horizontal plate 30 which 90 forms the main body portion of the paper carriage. The carriage is transversely movable as usual, on a suitable support or bed and, in the present instance, it is mounted upon a vertically movable shift frame. 95

In the preferred construction shown, the

shift frame comprises a pair of uprights 31, which are preferably formed of flat bars of sheet metal and are provided at their upper ends with rearwardly projecting arms 32, the 5 arms and uprights having inturned flanges 33 at their upper edges. The carriage supporting bed or track 34 comprises a transverse sheet metal bar and rests upon and is secured to the rear portions of the flanges 10 33 by screws 35. The transverse body portion or plate 30 of the carriage and the carriage body or track 34 are provided at their forward portions with race-ways 36 and 37 for anti-friction balls 38. The downturned 15 rear edge of the carriage plate 30 is provided with a strengthening strip 39 secured thereto by a series of screws 40 and a roller 41 on the central strip engages the upturned rear edge 42 of the plate 34. Front and rear 20 clips 43 and 44 fixed to the carriage bed engage respectively with a ball race 36 at the front edge of the carriage and with the bar 39 at the rear edge and hold the carriage in position upon the bed while permitting its 25 horizontal movement transversely of the machine.

The uprights 31 of the carriage supporting frame are arranged closely adjacent the inner faces of the side plates 10 of the main frame and slightly in front of the type bar segment 14. The upper portions of the uprights are provided with vertical slots 45 and guide studs 46 extend through the slots and abut against the inner faces of the side 30 plates 10, the studs being fixed to the side plates by screws 47 and being preferably provided with anti-friction rollers 48 (see Fig. 1^a) journaled thereon. The vertical side edges of the guide slots 45 engage the 35 rollers 48 and hold the upper portion of the vertical shift frame against movement in a direction longitudinally of the machine.

The lower ends of the uprights 31 are somewhat reduced in width, are bent inwardly away from the side plates 10 and are provided with notches 49 which engage the ends of a transverse rod 50 which is carried upon the rear ends of a pair of shift levers 51. These shift levers are arranged at opposite sides of the machine adjacent the side plates 10 and are fixed intermediate their ends upon a transverse rock shaft 52, the ends of which are journaled in the side plates 10 of the machine frame. The rear 45 ends of the shift levers loosely engage the transverse rod 50 between pairs of collars 53 (see Fig. 4) which are fixed to the rod by set screws 54 and the forked lower ends of the uprights 31 engage the extreme outer 50 ends of the rod 50 which project beyond the outer collars. A transverse strengthening bar 55 extends between rear ends of the shift levers 51 just in front of the rod 50, the ends of the bar being rigidly fixed to the 55 levers preferably by reduced end portions

thereon extending through slots in the levers and upset as shown in Fig. 1^b. A pair of counterbalancing springs 57 are connected at their lower ends to the transverse bar 55 and at their upper ends with a pair of studs 70 58 which project forwardly from the type bar segment 14. These springs partly counterbalance the weight of the vertically movable, carriage supporting frame and aid in effecting the vertical shift thereof. 75

To accurately guide the vertical movement of the carriage supporting frame and securely hold it against transverse movement, it is provided with guiding means which engage the side plates 10 at points adjacent and in rear of the type bar segment. For this purpose a pair of depending guide supporting plates 59 are provided. These plates are preferably formed of sheet metal and are provided at their upper ends with integral rearwardly turned flanges 60 which are fixed to the flanges 33 and to the carriage track or bed plate 34 by the screws 35. In the construction shown, spacing strips 61 are interposed between the flanges 60 and 33. 80 The guide supports 59 extend downwardly to a considerable distance and the extreme lower ends thereof are connected by a transverse brace bar 62. Long guide shoes 63 are mounted on the supports 59 by screws 64 and the upper and lower ends of the shoes are provided with rollers 65 which engage the inner faces of the side plates 10 of the machine frame. The screws 64 extend through horizontal slots 66 in the shoes and adjusting 85 screws 67 extend through rearwardly projecting ears 68 on the inner edges of the guide supports and these screws engage the inner edges of the guide shoes. By loosening the screws 64, the guide shoes 63 can be 90 adjusted by the screws 67 to take up any lateral play or wear and the shoes can then be securely clamped in adjusted position by 95 tightening the screws 64.

The rollers on the upper and lower ends of the guide shoes engage the side plates near the upper and lower edges thereof and securely hold the vertically movable shift frame against lateral vibration. The guide studs and rollers 46 and 48 which engage the upper portions of the uprights 31 of the vertically movable shift frame and the shift levers which engage the lower ends thereof, securely hold the frame against vibration in longitudinal direction. In this way the 110 frame is accurately held in position and against vibration even when the carriage is at either end of its movement. It should also be noted that the portions of the side plates 10 which co-operate with the guides of 115 the vertically movable shift frame, are located closely adjacent the heavy type bar segment which is rigidly secured to and braces these guiding portions of the side plates. For this reason the side plates 10 120

can be of lighter, cheaper construction than would otherwise be required. The arrangement is also such that by removing the guiding studs 46, the vertically movable carriage 5 supporting frame and the carriage thereon can be readily removed from the machine for repairs or the like.

The carriage supporting frame and carriage are held in normal position by gravity 10 with the counter-balancing springs 57 under tension. In this normal position, a pair of stop lugs or ears 69 which project forwardly from the upper portions of the guide supports 59 rest upon two stop screws 70 which 15 are adjustably threaded into the upper edge of the type bar segment 14. To effect the vertical shift, the forward ends of the shift levers are provided, preferably at each side of the machine, with two finger keys 71 and 20 72. The finger keys at the left-hand side of the keyboard are shown in Figs. 1 and 2 and those at the right-hand side of the keyboard in Fig. 3. The keys 71 are fixed to the upturned forward ends of the shift levers 51 25 and the keys 72 to the forwardly projecting arms of small bell cranks 73 that are connected by pivot studs 74 to the upturned forward ends of the shift levers. The depending arms of the bell cranks are provided 30 with outturned lugs 75 which extend between shoulders 76 and 77 formed on the front lower edges of the shift levers. Springs 78 coiled about the pivot studs 74 and engaging the shift levers and bell cranks, 35 hold the latter and the keys 72 in normal position with the lugs 75 engaging the shoulders 76. The lower arms of the bell crank 73 are connected by rearwardly extending links 79 to two stop dogs 80 that are loosely 40 mounted on the transverse rod 50 adjacent the inner collars 53 thereon. These dogs are connected together by a transverse rod 81 and are provided with end portions and shoulders 82 which coöperate with a pair of 45 adjustable stop screws 83. The latter, as shown, are threaded into a pair of forwardly projecting lugs 84 formed upon the lower portion of the type bar segment 14.

Normally the vertically movable carriage 50 supporting frame is in lowermost position as shown in Fig. 1 with the stop lugs 69 engaging upon the stop screws 70, and in this position the lower case type will be brought to the printing point. The spring-held bell 55 cranks 73 and links 79 normally hold the stop dogs 80 in their forward positions so that, when either of the shift keys 71 is depressed, the vertically movable frame and carriage thereon are raised until the shoulders 82 engage the stops 83 as shown in Fig. 60 2. The paper carriage is then raised to its highest position and, when the key levers and type bars are operated, the figures and punctuation marks are brought to the printing 65 point. If either one of the shift keys 72 is

operated, the bell crank 73 is turned about its pivot and the stop dogs 80, which are connected by the cross rods 81, are shifted rearwardly until the lug 75 on the bell crank lever 73 engages the shoulder 77 of the shift 70 lever. The continued downward pressure on the key 72 will then lift the carriage supporting frame and carriage in vertical direction but, in such cases, the upper ends of the stop dogs will engage the stops 83 and, as 75 shown in Fig. 3, the paper carriage will then be arrested in intermediate position for effecting the writing of capital or upper case letters. It is obvious that the two sets of shift keys at opposite sides of the keyboard 80 operate alike and, if desired, those at one side may be dispensed with.

To lock the carriage supporting frame in shifted position, a lever 85 is connected intermediate its ends by a pivot screw 86 to 85 the side plate 10 at the right hand side of the keyboard. This locking lever is provided at its upper end with a finger key 87 and at its lower end with a pair of locking lugs 88 which are arranged to coöperate 90 with a stud 89 on the side of the adjacent shift lever 51. Normally, the lower end of the locking lever is held by a spring 90 against a stop pin 91. But when the shift mechanism is operated to move the paper 95 carriage to its highest or to its intermediate position, the locking member can be shifted by its key to bring one of the two locking lugs into engagement with the stud 89 and thereby hold the parts in shifted position. 100 The lugs 88 are slightly undercut so that the spring 90 cannot withdraw them from engagement with the stud 89 unless downward pressure is exerted on one of the keys 71 and 72 or rearward pressure on the 105 key 87.

It is obvious that changes may be made in the details set forth, without departure from the essentials of the invention, as defined in the claims.

110

I claim as my invention:

1. In a front-strike typewriting machine, the combination with a main frame, of a vertically shifting frame comprising uprights having rearwardly projecting arms 115 at their outer ends, a carriage bed mounted on said arms, a platen carriage on said bed, a key actuated rocking frame mounted in said main frame and connected at its rear end to the lower ends of said uprights, guiding means on said main frame engaging said uprights for holding said shifting frame against movement in fore-and-aft direction, and depending adjustable guide shoes on said shifting frame and engaging said main 120 frame to take up lateral play in transverse direction, substantially as described.

2. In a front-strike typewriting machine, the combination with a main frame, of a vertically shifting frame comprising flat 130

sheet metal, side uprights having, at their upper ends, integral rearwardly projecting arms provided with integral horizontal flanges at their upper edges, and a carriage bed fixed to said flanges, means for vertically guiding the upper ends of said shift frame, and a key actuated rocking frame mounted in the lower portion of said main frame and pivotally connected at its rear end to the lower ends of said uprights, substantially as described.

3. In a front strike typewriter, the combination with a main frame comprising side plates, of a rigid, vertically disposed type bar segment fixed to and connecting said side plates, key actuated type bars pivoted on said support, a vertically shifting frame comprising side uprights arranged in front of said support and having arms at their upper ends projecting rearwardly over said support, a carriage bed mounted on said arms, a platen carriage guided on said bed, means for guiding the upper ends of said uprights, and a key actuated rocking frame mounted in the lower portion of said main frame and pivotally connected at its rear end to the lower ends of said uprights, substantially as described.

4. In a front-strike typewriter, a main frame comprising side plates, a rigid, vertically disposed type bar segment fixed to said side plates, a vertically shifting frame comprising side uprights arranged in front of and adjacent said segment and having arms at their upper ends projecting rearwardly over said segment, a carriage bed connected to said arms, a platen carriage mounted on said bed, means for guiding the upper ends of said uprights, key controlled actuating means connected to the lower ends of said uprights, and guide shoes depending from said carriage bed in rear of said segment and engaging the side plates of said main frame.

45 5. In a front-strike typewriter, a main frame comprising side plates, a rigid, vertically disposed type bar segment fixed to said side plates, a vertically shifting frame comprising side uprights arranged in front of and adjacent said segment and having arms at their upper ends projecting rearwardly over said segment, a carriage bed connected to said arms, a platen carriage mounted on said bed, means for guiding the upper ends of said uprights, key controlled actuating means connected to the lower ends of said uprights, guide supports fixed to said carriage bed and extending downwardly in rear of said segment, a cross brace connecting the lower ends of said supports, and adjustable guide shoes on said supports engaging the side plates of the main frame.

6. In a front-strike typewriter, the combination with a main frame, of a vertically shifting frame comprising side uprights and

a carriage bed, guides on said main frame coöperating with said uprights for holding said shifting frame against movement in fore-and-aft direction, key controlled actuating means connected to the lower ends of 70 said uprights, and means for holding said shifting frame against movement in transverse direction, comprising braced guide supports depending from said carriage bed between the sides of the main frame and 75 shoes adjustably mounted on said supports and having rollers at their upper and lower ends engaging the sides of the main frame.

7. In a front-strike typewriter, the combination with a main frame and a vertically shifting platen support, of a shift key lever pivoted in said main frame and connected at its rear end to said support, a normally fixed adjustable stop arranged adjacent the rear end of said lever to arrest the vertical 85 movement thereof and of said platen support, a shiftable stop dog, a second shift key pivotedly mounted on the forward end of said shift lever, and a link connecting said shift key to said shiftable dog, the latter arranged to coöperate in shifted position with 90 said fixed stop to arrest the movement of said platen support in an intermediate position.

8. In a front-strike typewriter, the combination with a frame, a carriage and a vertically shifting frame for supporting said carriage, of a key controlled rocking frame pivotally mounted in said main frame and connected at its rear end to the lower 100 end of said vertically shifting frame, said rocking frame having a forwardly projecting arm provided with a key fixed thereto, a bell crank having a second key pivoted on the forward end of said arm, a pair of connected stop dogs pivotally mounted on the rear end of said rocking frame and connected to said bell crank, and a pair of fixed stops with which said dogs coöperate to 105 variably limit the movement of said rocking 110 and said vertically shifting frames.

9. In a typewriting machine, the combination with a main frame, a platen and a shiftable support for said platen, of a pivoted shift lever for said platen support having a key at its forward end, a bell crank pivoted upon the forward end of said shift lever and having a second shift key, said bell crank being spring held in normal position and having a limited independent movement on said shift lever, a pivoted stop on the rear end of said shift lever, a link connecting said stop to said bell crank, and a normally fixed stop coöoperating with said pivoted stop to variably limit the movement 120 of said shift lever and said platen support. 125

10. In a front strike typewriter, the combination with a frame and a vertically shifting platen support, of a shift key lever pivoted in said frame and connected to said 130

- support, a stop member mounted at the rear end of said lever and bodily movable therewith, an auxiliary key pivoted on the forward end of said shift lever, a link connection between said auxiliary key and said stop member, and a fixed stop arranged to coöperate with said stop member to variably limit the movement of said lever and said vertically shiftable platen support. 65
- 10 11. In a front strike typewriter, the combination with a frame and a vertically shiftable platen support, of a shift key lever pivoted in said frame and connected to said support, a shiftable stepped stop mounted at the rear end of said lever and bodily movable therewith, an auxiliary shift key controlling said stepped stop, and a normally fixed adjustable stop arranged to coöperate with said shiftable stepped stop to variably limit the movement of said vertically shiftable platen support. 70
- 15 12. In a front strike typewriter, the combination with a frame, a carriage and a vertically shiftable frame for supporting said carriage, of a key controlled rocking frame pivotally mounted in said main frame and connected at its rear end to the lower end of said vertically shiftable frame, said rocking frame having a forwardly projecting arm provided with a shift key, a pair of connected stop dogs pivotally mounted on the rear end of said rocking frame, an auxiliary shift key for actuating said rocking frame and controlling said dogs, and a pair of fixed stops with which said dogs coöperate to variably limit the movement of said rocking and said vertically shiftable frames. 75
- 20 13. In a front-strike typewriter, the combination with a main frame, of a vertically movable shift frame comprising side up- 80
- 25 rights and a transverse carriage bed between the upper ends of said uprights, a key actuated rocking frame mounted in said main frame and pivotally connected at its rear end to the lower ends of said uprights, guiding means on said main frame engaging said uprights to hold said shift frame against movement in fore-and-aft direction, and depending adjustable guide shoes on said shift frame and engaging said main frame to take up lateral play in transverse direction, substantially as described. 85
- 30 14. In a front-strike typewriter, a main frame comprising side plates, a rigid vertically disposed type bar segment fixed to and connecting said side plates at points in front of the rear edges thereof, a vertically movable shift frame comprising side uprights and a transverse carriage bed arranged above said segment, a key actuated rocking frame mounted in the lower portion of said main frame and having arms pivotally connected at their rear ends to the lower ends of said uprights, means for guiding the upper 90
- 35 ends of said uprights, arranged to hold said shift frame against movement in fore-and-aft direction, and guide shoes depending from said carriage and engaging the side plates of said main frame at points adjacent said type bar segment. 95
- 40 15. In a double-shift, front-strike typewriter, the combination with a main frame, of a vertically movable, platen-supporting shift frame having side uprights, a rocking frame mounted in said main frame and pivotally connected at its rear end to the lower ends of said uprights, main and auxiliary shift keys for moving said rocking frame and said vertically movable shift frame, and stop devices arranged adjacent said vertically movable shift frame and comprising a pair of normally fixed, adjustable stops, one at each side of the main frame, for determining the normal lowermost position of said shift frame, a second pair of normally fixed, adjustable stops, one at each side of the main frame, for determining the uppermost position of said shift frame, and a pair of shiftable stop dogs controlled by the auxiliary shift key and arranged to coöperate with said second pair of adjustable stops to arrest the movement of the shift frame in an intermediate position. 100
- 45 16. In a front-strike typewriter, a main frame comprising side plates, a rigid, vertically disposed type bar segment fixed to and connecting said side plates, a vertically movable shift frame comprising a carriage bed and side uprights arranged adjacent said segment, a rocking frame mounted in said main frame and having arms pivotally connected at their rear ends to the lower ends of said uprights, normally fixed adjustable stops mounted on said type bar segment for limiting the movement of said shift frame, a shiftable stop dog arranged to coöperate with one of said fixed stops to arrest said shift frame in an intermediate position, and actuating keys for said rocking frame and said stop dog. 105
- 50 17. In a front-strike typewriter a main frame, a vertically movable shift frame comprising side uprights and a transverse carriage bed extending between the upper ends of said uprights, a platen carriage mounted on said bed, means for guiding the upper portion of said shift frame, a key actuated rocking frame journaled in said main frame and having rearwardly projecting arms, and a rod extending between the rear ends of said arms, said rod having projecting end portions detachably and pivotally engaged by the lower ends of said uprights. 110
- 55 18. In a front-strike typewriter, a frame comprising sheet metal side plates, front and rear transverse members connecting said side plates, a transverse, vertically disposed, rigid type bar support of cast metal con- 115
- 60

necting said side plates in front of the rear ends thereof, upwardly and rearwardly striking type bars pivotally mounted on said support, key levers pivoted below said type bars and operatively connected thereto, a carriage and carriage bed arranged above and in rear of said type bar support, a ver-

tically movable shift frame whereon said bed is mounted and means coöperating with said side plates for guiding said shift frame, 10 said guiding means being arranged in front and rear of and closely adjacent said type bar support.

HUBERT K. HENRY.
